UNITED STATES PATENT OFFICE.

SYLVESTER EBERLY, OF OTTOKEE, ASSIGNOR OF ONE-HALF TO GEORGE KESLER, OF WAUSEON, OHIO.

WIRE-FENCE-STAY FASTENING.

SPECIFICATION forming part of Letters Patent No. 460,913, dated October 6, 1891.

Application filed June 9, 1891. Serial No. 395,633. (No model.)

To all whom it may concern:

Be it known that I, SYLVESTER EBERLY, a citizen of the United States, residing at Ottokiee, in the county of Fulton and State of Ohio, have invented certain new and useful Improvements in Wire-Fence-Stay Fastenings; and I do hereby declare the following to be a full, clear, and exact description of the invention, such as will enable others skilled in the art to which it appertains to make and use the same.

This invention relates to wire fences, and chiefly to the means for fastening the wire stays to the fence-wires.

The improvement consists of the novel features and the peculiar construction and combination of the parts which will be herein-after more fully described and claimed, and which are shown in the annexed drawings, in which—

Figure 1 is a side view of a fence embodying my invention. Fig. 2 is a detail view showing the fastening-plate mounted on the fence-wire. Fig. 3 is a front view of a crossing of the stay and fence wires, showing the application of the invention. Fig. 4 is a perspective view of the parts shown in Fig. 3.

The fastening-plate C is provided with the slots a and b, which extend at about right angles to each other and cross midway of their ends, forming the four wings e. These fastening-plates will be of proper size, and the slot b will be just wide enough to receive the fence-wire and the slot a equal in width to the gage of the stay-wire. The fastening-plate will be deflected between its ends on a line corresponding with the position of the slot a.

The fence is constructed in the usual manner, being composed of posts E and the longitudinal wires A. At the place where it is desired to locate the stay-wire a fastening-plate C is placed on the top fence-wire, as shown in Fig. 2, the wire A entering the slot b. The stay-wire B is slipped down between the fence-wire and the angle formed between

the deflected portions of the said plate. A plate C is similarly arranged on the fence-wire below the said top wire, and the stay-wire is pushed down. This operation is repeated until a fastening-plate is provided for each fence-wire or as many of the fence-wires as required. The fastening-plates are now straightened either by a mallet and block, the block being placed on one side of the plate, and the latter struck one or more blows on the opposite side, or by a clamp, the plate being compressed between the jaws of the clamp. The straightening of the plate crimps the stay-wire about the fence-wire, as most clearly shown in Fig. 4, and causes the wings e to bind on the sides of the stay and fence wires, as shown most clearly in Figs. 3 and 4.

It will be observed that the wings e fill the angular space between the fence and the stay-wires and bear against the wires close in the angles, thereby preventing any possible movement.

Having thus described my invention, what I claim, and desire to secure by Letters Patent, is—

1. The combination, with a fence-wire and a stay-wire, of a fastening-plate having slots a and b, which slots cross midway of their ends and form the four separate and independent wings e, the latter binding at their inner edges against the sides of the said wires, substantially as described.

2. A fastening-plate for the purpose described, having slots a and b, which cross midway of their ends, and having the four wings e separate and independent, the plate being deflected between its ends on a line corresponding with the position of one of the said slots, substantially as described, for the purpose set forth.

In testimony whereof I affix my signature in presence of two witnesses.

SYLVESTER EBERLY.
